UNITED STATES PATENT OFFICE.

SAMUEL H. RANSOM, OF ALBANY, NEW YORK.

DESIGN FOR THE PLATES OF A COOKING-STOVE.

Specification forming part of Design No. 6,726, dated June 24, 1873; application filed April 18, 1873.

To all whom it may concern:

Be it known that I, S. H. RANSOM, of the city and county of Albany and State of New York, have invented a Design for the Plates of a Cook-Stove, of which the following is a specification:

The nature of my design is fully represented in the accompanying engraving, to which reference is made.

A A A represent the ornaments for the center of the doors. They are all similar in form and combination, the center being a cross formed of four sexagon-shaped figures

to represent a jewel, with a finish of scrolls at the top and bottom, and in each corner of cross a winged-shaped extension.

I do not claim the ornamentation on the outer edge of the doors, nor the formation of any of the moldings.

What I claim as my invention is—

A design for the plates of a cook-stove, substantially in the manner above mentioned.

S. H. RANSOM.
